CURTAIN FIXTURE

Filed June 21, 1928

UNITED STATES PATENT OFFICE.

GEORGE M. KENNEY, OF CRANSTON, RHODE ISLAND, ASSIGNOR TO KENNEY MANUFACTURING COMPANY, OF CRANSTON, RHODE ISLAND, A CORPORATION OF RHODE ISLAND.

CURTAIN FIXTURE.

Application filed June 21, 1928. Serial No. 287,320.

The curtain rod forming the subject matter of my present invention while of the formed sheet metal type, represents a new structural type adapted for a very considerable range of drapery uses.

The standard C-shaped rod while having many good points which justified its popularity had some obvious defects and various limitations in use.

10 My new type of rod is capable of use in both single and telescopic form, in straight or curved end equipment, in inserted or suspending relation to the drapery, and while serving all the uses of the ordinary curtain 15 or portière rod may be used as a traverse equipment in which it is combined with my carriage as will appear in the following specification and in the drawings. In the drawings I have illustrated characteristic 20 embodiments as follows:

In Fig. 1 I have illustrated a typical form of rod.

Fig. 2 a plan view of the same used as a sash or portière rod.

25 Fig. 3 a plan view of an installation as a curved end rod.

Fig. 4 a view of the same in transverse equipment.

Fig. 5 an enlarged sectional view through 30 the rod and carriage shown in Fig. 4, and

Figs. 6 and 7 are similar sections illustrating modifications in carriage type.

Referring first to Fig. 1 it will be noted that the structure of the rod is essentially different from the ordinary type of sheet metal rod which is generally C-shaped in cross section, giving a flat external face with rounded top and bottom edges and an open back. This open back is only partly concealed by the drapery when in place and not concealed at all if the draperies are down, as is frequently the case in summer weather. The edges of these C-shaped rods are furthermore apt to catch in the heading of the curtains when the curtains are being run on or adjusted and if these unprotected edges are dented or marred in handling, they are apt to cut threads or ravel material or otherwise give trouble. Furthermore, this open back necessarily represents a factor of weak-

ness in the rod as downward or twisting strains find no support on that side and at points of attachment, as for example, where a bracket or hook is used there is a very weak basis in the rod for satisfactory assembly or 55 mounting.

It will be noted that my rod by reason of its structure possesses a very considerable amount of strength. While its exact shape may be varied it preferably consists of a 60 rounded top portion 1¹ with depending lateral portions 1² and an upwardly and inwardly turned lower edge 1³ leaving the free edge as a rail or flange 1⁴. The mechanical possibilities of this flange will be discussed 65 later.

Before dealing with the mechanical possibilities of this simple structure I would point out its aesthetic potentialities because in this art the drapery rod inevitably becomes an addition to or subtraction from the aesthetic effect of the room. The inverted U-shape of the rod affords a pleasing and original design and by positioning the curved closed edge 1¹ uppermost it gathers 70 no internal dust or lint.

It is to be noted, however, that inasmuch as the curtain rod is usually observed from below, it would be supposed that an open lower edge would be unsightly. In this regard my rod and upwardly turned portion 1³ becomes the saving factor. It will be observed, as in Fig. 1, that the upturned portion of the bend 1² is so proportioned to the width of the opening X between these 80 flanges that except as viewed from immediately below, which would represent a most unusual position of the observer, the inner face of the upturned portion 1³ which is the same as the outer face of the rod material, appears to ordinary observation to close the gap X so that hollowness of the rod is 85 not at all apparent.

Turning now from the matter of appearance to the matter of mechanical utility, it 95 will be seen that this rod structure combines to form rods of the adjusting or sliding type. In such the inwardly and upturned bottom flanges play an important mechanical part as they afford a very complete mechanical 100

interlock along parallel edges and in opposition to the bow shaped part 1¹. Such an interengagement not only gives very great vertical rigidity but is capable of handling 5 very considerable lateral or torsional strains so that rods made of comparatively thin stock show much greater strength than rods of other types and of thicker stock.

These inwardly and upwardly turned 10 flanges 1² however have even a further and more remarkable utility because they make possible the use of the rod in a traversing equipment. In such equipments the desirability of concealed traversing cords is very 15 great. Such concealed structures have always been very expensive to make and only available in high priced equipment when used on jobs laid out and installed by professional interior decorators.

20 Referring to Fig. 5 it will be seen that this inwardly upturned pair of flanges which I have previously described as contributing to the aesthetic effect of the rod and to its mechanical strength affords a pair of spaced 25 flanges or tracks 1⁴ on which traversing trucks or rollers can be supported and guided so that as illustrated in Fig. 5 a drapery suspending hook 4 can be hung from the axle 2 of the rollers 3 which bear on the edges 1⁴. 30 It will be noted that in the telescopic rod construction as shown in Fig. 5, the inner rod member 1^a is made from stock of slightly narrower width than the outer rod member 1^b so that the edges 1⁴ of both rod members are of uniform height, thus providing 35 a smooth and even track on which the traverse rolls or slides.

It will be further noted that the pull cord or cords C may be run through the rod or 40 rods above the axle 2 so as to be concealed and guided through the rod without danger of fouling or slackening or escaping through the opening X on the lower side of the rod. The tracks or rollers may be variously 45 shaped to take advantage of the rod construction. In Fig. 6 I have shown a modified form using double flanged rollers 5 so that each roller straddles the rail or track formed by the edge 1⁴. In Fig. 7 I have shown a 50 very simple and inexpensive type of support. In this the member 4 may be a smooth hard button shaped member 6 which will slide on the tracks or rails formed by the edges 1⁴.

55 As indicated in Figs. 2 and 3, the rod may be installed as a sash or portière rod or as a bent end or projecting window frame rod. In either case it may be supported on almost any conventional type of bracket. In the 60 form shown I have illustrated a simple hook.

As heretofore suggested the design and finish of such rods may be widely varied and the rods sold as standard stock rods or as extension rods or as traverse rods with or 65 without contained rollers, pulleys, slides or

other traverse elements. This makes it unnecessary for the dealer to carry in stock a large number of both curtain and traverse rods. Instead he can carry a few standard rods and by selling the traverse parts as a 70 unit or set the curtain rod can be readily adapted for traverse work. It is to be noted that as a traverse rod on account of the thinness of the spaced rails, the edge contact offers so little friction that no lubrication is 75 necessary. This is important as the necessity of lubrication in most of such devices has created a danger too often realized on spotted or soiled curtains.

While my invention has that versatility 80 and adaptability which makes it capable of a great variety of uses, I am not to be understood as limited to any one of them, but desire to protect my concept in its fundamental 85 simplicity.

What I therefore claim and desire to secure by Letters Patent is:

1. A curtain or drapery rod consisting of a length of sheet metal formed to present a pair of substantially parallel spaced 90 front and rear walls and an arched top wall connecting said front and rear walls, the lower edges of said front and rear walls being bent inwardly and upwardly as flanges which tend to strengthen and brace said 95 front and rear walls and to conceal the bottom opening of the rod when viewed from the normal angle of vision.

2. A curtain or drapery rod consisting of a length of sheet metal formed to present 100 a pair of substantially parallel spaced front and rear walls merging into a connecting top wall, the lower edges of said front and rear walls being bent inwardly and upwardly in spaced parallel relation to each other 105 and to the front and rear walls as flanges which tend to strengthen and brace said front and rear walls and to conceal the bottom opening of the rod when viewed from the normal angle of vision.

3. A curtain or drapery rod consisting of 110 duplicate lengths of sheet metal formed to telescope within each other and each present a pair of substantially parallel spaced front and rear walls and an arched top wall connecting the upper edges of said front and rear walls, the lower edges of said front and rear walls being bent inwardly and upwardly as flanges which tend to strengthen and brace said front and rear walls and to conceal the bottom opening of the rod when viewed from the normal angle of vision, and the flanges of one rod section closely 115 engaging those of the complementary rod section to increase the strength and rigidity 120 of the rod.

4. A curtain or drapery rod consisting of 125 duplicate lengths of sheet metal formed to telescope within each other and each present a pair of substantially parallel spaced front 130

and rear walls merging into a connecting top wall, the lower edges of said front and rear walls being bent inwardly and upwardly in spaced parallel relation to each other and to the front and rear walls as flanges which tend to strengthen and brace said front and rear walls and to conceal the bottom open-

ing of the rod when viewed from the normal angle of vision, and the flanges of one rod section closely engaging those of the complementary rod section to increase the strength and rigidity of the rod.

In testimony whereof I affix my signature.

GEORGE M. KENNEY.
